[57] ABSTRACT

Citrus fruit peels and pulp are treated by coking in the aqueous phase in the absence of air or oxygen followed by heating of the resulting coke to give water insoluble essential oils such as orange oils. A carrier gas such as nitrogen preferably is used to entrain the hydrocarbons evolved by heating the coke.

4 Claims, 1 Drawing Figure

PROCESS FOR TREATING CITRUS WASTES TO OBTAIN WATER INSOLUBLE ESSENTIAL OILS

CROSS REFERENCE TO COPENDING APPLICATION

This application is a continuation-in-part of commonly assigned application Ser. No. 887,684 filed Dec. 23, 1969, and now abandoned itself a continuation-in-part of application Ser. No. 780,080, filed Nov. 29, 1968 and now U.S. Pat. No. 3,507,788.

BACKGROUND OF THE INVENTION

The essential oils industry has for many years resorted to substantially the same processes for extracting citrus oils from citrus fruits. It has made little use of peels and pulp except for the obtaining of low grade oils.

Generally, the peel after expression of the oil still contains essential oils retained by the albedo. These oils can be recovered by steam distillation of the waste peel but are of mediocre quality, typical of distilled citrus oils.

The peels and pulp can also be soaked in hot lime solution to gelatinize the pectins. The resulting mass is then submitted to high pressure to express a watery liquid containing oil which is concentrated for the production of molasses. During concentration distilled oil called "stripper oil" can be recovered but this oil is very harsh and can only be used in non-flavoring applications such as in insect sprays; etc.

SUMMARY OF THE INVENTION

In accordance with the claimed invention it has been discovered that when citrus fruit wastes, including peels and pulp, are coked in the liquid phase in the absence of air or oxygen and the coke so formed is heated, it will liberate an oil fraction consisting essentially of essential oils in an appreciable yield.

DETAILED DESCRIPTION OF THE INVENTION

In accordance with the claimed invention, citrus wastes including peels and pulps of oranges, tangerines, lemons, grapefruits are coked at a temperature ranging from 350° to 750°F. and preferably between about 385° and 550°F. in the liquid phase in the absence of air or oxygen under autogeneous pressure of about 300 to 1000 p.s.i.g. for a coking time ranging from about 0.1 minute to 2 hours and preferably from 1 minute to 10 minutes under turbulent flow conditions characterized by a Reynolds number which is in excess of 2,000 and preferably in excess of 4,000. The Reynolds number is defined as:

$$N_{Re} = \frac{DV}{\mu}$$

where:

N_{Re} = Reynolds Number

D = Inside Diameter of tube, ft.

V = Average linear velocity, ft/sec

μ = Fluid viscosity, lb/cu. ft.

μ = Fluid viscosity, lb/ft. (sec)

While not wishing to be bound by any particular theory it is believed that under the operation condition of the present process the molecules of essential oil constituents coke more slowly than the molecules of other

citrus waste constituent and become occluded in the coke formed by the latter.

BRIEF DESCRIPTION OF THE DRAWING

5 The invention can best be described by reference to the single FIGURE of the accompanying drawing, which shows apparatus for treating citrus wastes to obtain citrus oils.

DESCRIPTION OF SPECIFIC EMBODIMENTS

10 In the apparatus shown in the figure, citrus fruit peels and pulp are fed into a hopper 10 communicating with a masticator consisting essentially of a gear pump with a cutter head. The broken up waste then passes to piston pump 7 which pumps it through heat exchanger 16 and then to heater 8 which has a coker tube from which air and oxygen are excluded by vacuum, by flushing with an inert gas such as nitrogen or by other means. The coked slurry is in heat exchange relationship with 15 the feed by pump 7 and then passes on to a filter 20 where the coke is separated from the major portion of the water. At this point it should be noted that for the purpose of the invention a filter may be replaced here with a centrifuge or by a cyclone separator. The filter coke which results from the separation procedure is fed through line 24 to kiln 26 while the waste water passes through line 22 for subsequent use as washwaters and the like. In kiln 26 the wet cake is contacted with steam 20 in order to distill overhead the monoterpenes hydrocarbons and the water. The overhead is condensed in condenser 28 to separate the gas phase (line 35), citrus oil (through line 37) and the water phase (through line 39) in separator 30. A substantially dry coke is taken 25 off the bottom of the kiln and may be used as a fuel to heat reactor 18 and/or processed to produce activated carbon or used as cattle feed. The gas stream taken off the separator through line 35 is useful as a source of high purity carbon dioxide for dry ice manufacture and 30 the like. The effluent water taken off through lines 22 and 39 can be reused but they will have a substantial Biological Oxygen Demand which can be reduced, if desired, by air oxidation or biological treatment. The invention is further illustrated by the following examples.

EXAMPLE I

In an example of the practice of the invention, 1100 grams of orange peels and 440 grams of distilled water 50 were slurried in a Waring Blender. The blend was placed in a 1960 ml. rocking autoclave. The autoclave was evacuated to about 5 lb. p.s.i.g. and heated to 410°F. The autoclave was held at this temperature for 2 hours, cooled and 4760 ml. of gas, recovered.

55 The coke material in the autoclave was poured out and 200 ml. of water used to wash out the autoclave. Charged 1538 grams of coke slurry to vacuum filter.

Recovered 1025 grams of liquid, pH-5 and 512 grams of wet solids. The wet solids were placed in a round 60 bottom flask fitted with a heating mantle and a water condenser. The flask was heated and a slow stream of nitrogen was introduced that acted as a carrier gas. The flask was heated to about 400°F. and 338 grams of liquid were recovered. The liquid was placed in a separatory funnel and 12 grams of an upper oily layer, identified as orange oil, was recovered. 165 grams of damp coke was recovered from the flask. The coke was dried

on a steam plate and amounted to 108 grams. The tests are shown as follows in Table I.

Table I

Sample	Orange Oil	Dry Coke	Gas
Yield, Wt.% Basis	1.09	9.8	0.845
Peels			
Sample No. L-68-	103A3	103A4	103G1
Nitrogen, Wt.%	0.01	1.18	—
Sulfur, Wt.%	—	0.21	—
Ash, Wt.%	—	4.5	—
Carbon, Wt.%	—	62.9	—
Hydrogen, Wt.%	—	5.6	—
Bromine No.	128.3	—	—
Infrared Spectrum	Identified as limonene		
Odor	Orange	—	—
Mole %	—	—	—
H ₂	—	—	0.2
C ₂	—	—	0.1
C ₃	—	—	0.2
CO ₂	—	—	98.6
A ₁₂	—	—	0.6

660 grams of orange peels and pulp slurried with 440 grams of water in a Waring Blender. 100 grams of the slurry was removed and tested as follows:

Solids, wt.%	10.8
Ash, wt.%	0.038
COD, mg. O ₂ /L	100,000
pH	4

The remaining slurry was placed in a 1960 ml. autoclave. The autoclave was flushed with nitrogen, sealed, and heat applied as follows:

Time	Temp. °F.	Pressure, psig
10 AM	80	0
11 do.	272	25
12 NOON	408	300
1 PM	410	300
2 do.	404	275

The heat was shut-off and the autoclave cooled to room temperature, 82°F. The pressure was 35 psig. The autoclave was depressured and a total of 2260 ml. of gas was collected. 971 grams of material was removed from the autoclave. The product was filtered. Recovered 778 grams of filtrate and 175 grams of filter cake (coke). The coke had the odor of limonene.

EXAMPLE III

261 grams of orange peel and pulp slurried with 600 grams of water in a Waring Blender. The slurry was placed in a 1960 ml. autoclave. The autoclave was flushed with nitrogen and sealed. The temperature was 84°F. and the gage reading (psig) was zero. The autoclave was heated to 550°F. and held at this temperature for 2 hours. The temperature-pressure relations at the treating conditions are as follows:

Elapse Time, Hrs.	Temp. °F.	Pressure psig
0	558	1100
1	552	1100
2	554	1100

The heat was shut-off and the autoclave cooled to 82°F. The pressure on the autoclave was 125 psig. Vented autoclave. Recovered 799 grams of liquid and coke from the autoclave. A trace of clear oil was noted that had the odor of limonene. The coke was separated from the oil by filtration. Recovered 50 grams wet coke and 749 grams filtrate. The coke was dried on a steam plate, recovered 35.0 grams. The following tests were carried out:

10

Sample	Charge	Filtrate	Dry Coke	Orange Oil	Gas
COD, mg O ₂ /L	12,200	26,970	—	—	—
Ash, wt.%	0.23	—	2.48	—	—
Carbon, wt.%	—	—	72.6	—	—
Hydrogen, wt.%	—	—	6.2	—	—
Sulfur, wt.%	—	—	0.1	—	—

25

EXAMPLE IV

261 grams orange peel and pulp slurried with 600 grams of water in a Waring Blender. The slurry was placed in a 1960 ml. autoclave. The autoclave was flushed with nitrogen and sealed. The temperature was 88°F. and the gage reading (p.s.i.g.) was zero. The autoclave was heated to 450°F. and held at this temperature for 2-hours. The temperature-pressure relations at the treating conditions are as follows:

35

Elapse Time, Hours	Temp. °F.	Pressure psig
0	458	450
1	458	450
2	454	450

The autoclave was then cooled to 90°F., the pressure was 75 p.s.i.g. Vented gas from autoclave. A 541 gram portion of the liquid-coke product was then filtrated. It was noted that a trace of orange oil floated on the liquid-coke from autoclave. Filtered, recovered 410 grams filtrate and 57 grams of wet coke. The coke when dried on steamplate weighed 18 grams. During drying of coke a strong odor of limonene was noted.

CO ₂	—	—	—	97.3	

While nitrogen has been used in the above examples it will be appreciated that other inert gases are equivalent thereto for the purposes of the invention. Similarly, it will be appreciated that the process of the invention can also be used for the production of water insoluble essential oils from other sources than citrus fruits.

The citrus oils obtained by the present invention find utility in the essential oils industry as components of perfume and flavoring formulations.

I claim:

1. Process for treating citrus wastes to obtain essen-

tial oils comprising coking said citrus wastes in the aqueous phase under autogeneous pressure at a temperature of about 350° to 750°F. in the absence of air or oxygen for a coking time ranging from about 0.1

5 minute to about 2 hours under turbulent flow conditions characterized by a Reynolds number in excess of 2000, to form coke mixed with essential oils separating the coke so formed from the aqueous phase and heating said coke to distill off said essential oils.

10 2. Process according to claim 1 wherein an inert carrier gas is used during said heating of said coke to entrain said oils therewith.

15 3. Process according to claim 2 wherein said gas is nitrogen.

4. Process according to claim 1 wherein said coke is heated to about 400°F. to distill off said hydrocarbons.
